LUGGAGE LOCK

Abraham Levine, Mendham, N.J., assignor to Sardis Luggage Company, Sardis, Miss., a corporation of Mississippi

Filed Nov. 3, 1959, Ser. No. 58,202

Term of patent 14 years

(Cl. D50—7)

Fig. 1

Fig. 2

Fig. 3

Fig. 4

Fig. 5

Fig. 6

Fig. 1 is a top plan view of the luggage lock embodying my new design, and shown in closed condition;

Fig. 2 is an end view of the same, viewed from the left of Fig. 1;

Fig. 3 is an end view of the same, viewed from the right of Fig. 1;

Fig. 4 is a side elevational view of the same in closed condition; the undisclosed side of the luggage lock is substantially plain in appearance.

Fig. 5 is a top plan view of the same shown in open condition; and

Fig. 6 is a side elevational view of the same in open condition.

I claim:

The ornamental design for a luggage lock, as shown and described.
